UNITED STATES PATENT OFFICE

STANLEY W. NICHOLSON, OF TOLEDO, OHIO, ASSIGNOR, BY MESNE ASSIGNMENTS, TO
THE DURA COMPANY, OF TOLEDO, OHIO, A CORPORATION OF OHIO

GEAR SEGMENT FOR WINDOW REGULATORS

Application filed October 23, 1925. Serial No. 64,471.

The invention relates to window regulators and is particularly applicable to mechanisms for raising and lowering windows of motor vehicles. One of the objects of the invention is the provision of an improved window regulator which may be cheaply manufactured. Another object is to provide a window regulator having an improved actuating mechanism which is so constructed that it has a long life of operation. A further object is to provide a simple arrangement of window regulator, including a mounting plate, a lifter arm and a convolute counterbalancing spring.

With these as well as other objects in view the invention resides in the novel features of construction and combinations and arrangements of parts as more fully hereinafter set forth.

In the drawings:

Figure 1 is an interior side elevation, partly broken away, and illustrating a window regulator embodying my invention;

Figure 2 is an enlarged interior side elevation of the window regulator;

Figure 3 is a bottom plan view thereof;

Figure 4 is a cross section on the line 4—4 of Figure 2;

Figure 5 is an enlarged cross section on the line 5—5 of Figure 2.

As shown in the present instance, my invention is applied to a motor vehicle door 1 having in its upper portion the opening 2 and in its lower portion the chamber 3. 4 is the window in the nature of a glass plate, which is adapted to be vertically slid from a position closing the opening 2 into the chamber 3.

The regulator for raising and lowering the window includes the lifter arm 5 suitably connected at its outer end to the window as by means of the roller 6 upon the lifter arm engaging in the channel 7 secured to the lower edge of the window. This lifter arm is pivotally mounted upon the mounting plate 8, the upper portion of which is secured to the lock board 9 of the door. The pivot in the present instance is formed by the pin 10 which is journaled in the lower portion 50 of the mounting plate below the lock board

and to the outer side of which is fixedly secured the inner end of the lifter arm. For swinging the lifter arm, I have provided the gear segment 11 which is rigidly secured to the lifter arm with its teeth concentric with the pin 10. 12 is a driving pinion having its teeth meshing with those of the gear segment 11 and 13 is a handle suitably connected to the driving pinion to rotate the latter in either direction. In the present instance I have provided between the handle and the driving pinion suitable locking mechanism within the bell-shaped housing 14 for normally holding the lifter arm and consequently the window in its various adjusted positions.

To reduce the cost of manufacture of the window regulator and at the same time to increase its life of operation the gear segment 11 is formed from a sheet steel blank of substantially uniform thickness and its teeth 15 are rolled and, as shown particularly in Figures 2 and 5, have a greater width than the main portion of the body 16 of the gear segment. Furthermore the portion of the body of the gear segment adjacent to the bases of the interdental spaces 17 is of greater width than the main portion of the body owing to the lateral projections 18, which assist in reinforcing the teeth. In rolling, a partially finished blank having roughed-out over sized teeth is brought into engagement when cold with a tooth-forming die, one of the members being rotated so that the material forming the bearing surfaces of the teeth is made more dense and is hardened in addition to being laterally extended in both directions. This is also true of the material at the bases of the interdental spaces. Thus it is seen that my gear segment has generated teeth of maximum accuracy which are integral with the body and are provided with extended hardened and burnished bearing surfaces thereby increasing the wearing qualities of the gear segment and the actuating mechanism of the window regulator as well as effecting smoother tooth action.

For counterbalancing the weight of the window 4 I have provided the convolute 100

spring 19 which is located at the inner side of the mounting plate 8 and below the lock board 9 and surrounds the inner end of the pin 10. This convolute spring has its inner end secured to the pin 9, in the present instance by engaging in the slot 20 in the pin, and has its outer end secured to the mounting plate. This latter connection is made by means of the transverse inturned ear 21 upon the right-hand inclined lower edge 22 of the mounting plate, the ear preferably having at its inner edge the upwardly extending projection 23 for preventing the outer hooked end of the convolute spring from becoming laterally disengaged from the ear. There is also a corresponding ear 24 upon the left-hand inclined lower edge 25 of the mounting plate for engagement by the outer end of the convolute spring in the event that the window regulator is to be used in a door on the opposite side of the motor vehicle.

What I claim as my invention is:

1. A sheet metal toothed member for window regulators having teeth of greater width than its body and provided with bearing surfaces of greater hardness than its body, said teeth and body being formed from a single piece of sheet metal.
2. A toothed member for window regulators formed from a piece of sheet metal of substantially uniform thickness and having the teeth and the portions of the body at the interdental spaces solid and of greater width than its body.
3. A toothed segment for window regulators formed from sheet steel of substantially uniform thickness and having rolled teeth of greater width than the body of the segment and provided with lateral reinforcements at the bases of the interdental spaces.
4. A sheet metal toothed member for window regulators having a body and teeth integral therewith and provided with extended hardened bearing surfaces.

45 In testimony whereof I affix my signature.
STANLEY W. NICHOLSON.
